METAL BLANK AND METHOD OF BLANKING

Robert H. Maddock, Lakewood, Ohio, assignor to
The Midland Steel Products Company, Cleve-
land, Ohio, a corporation of Ohio

Original application November 26, 1938, Serial
No. 242,554. Divided and this application Jan-
uary 23, 1941, Serial No. 375,647

6 Claims. (Cl. 164—17)

This invention relates to new and useful im-
provements in sheet metal blanking and is a divi-
sion of application Serial No. 242,554 filed No-
vember 26, 1938.

An important object of the invention is to pro-
vide special shaped sheet steel stock and a meth-
od of laying out special blanks or pieces thereon,
which results in obtaining a greater number of
such pieces per ton of sheets than can be ob-
tained by blanking the pieces from the usual
rectangular sheets heretofore supplied by the
steel industry.

Other objects and advantages of the invention
will become apparent during the course of the
following description.

In the accompanying drawing forming a part
of the application and wherein like numerals
are employed to designate like parts throughout
the several views—

Fig. 1 is a plan of the new form of sheet illus-
trating one manner of nesting and blanking sub-
rails of automobile frames therefrom and,

Fig. 2 is a plan of the old form of rectangular
sheet illustrating applicant's improved manner
of nesting these special blanks thereon.

In order to appreciate the economies derived
from the special form of sheet and blanking
disclosed herein, prior practice must be under-
stood. In the case of sheet steel ordered by com-
panies which manufacture automobile frames or
parts thereof having longitudinal co-planar
bends or offsets to lower the center of gravity
of the frame, it has been the practice to pur-
chase rectangular sheets 1 of Fig. 2 under 46, 60
and 72 inches in width, since this has been the
only shape in which steel mills furnish this stock
and any sheets exceeding these width sell for
premium prices. Therefore, the fabricating com-
panies make it their practice in ordering sheet
steel for this purpose, to order sheets as much
below the premium priced sheets as are com-
mensurate with obtaining the largest number of
rail or sub-rail blanks per-ton-cost of steel or-
dered. These blanks usually each average 6 to
12 inches wide and from 5 to 15 feet long. In
addition, the sub-rails have one co-planar offset
or kickup portion 2, while the main rails usually
possess two of such kickup portions. Thus, these
blanks are of generally elongated, somewhat ser-
pentine form, and being tapered in addition,
makes economical blanking quite a huge cost
problem when hundreds of thousands of these
blanks are involved.

In the case of sub-rail blanks B as shown in
the drawing, which taper from a wide end 4

down to a narrow kickup end 2, peculiar nesting
difficulties are encountered to economically pro-
duce these blanks. If the blanks are not laid
out closely contiguous, side by side, with one con-
forming as closely as possible to the contour of
the next adjacent blank, as for example, when
the wide ends 4 of a group are arranged parallel
against the edge 5 of the sheet, this arrangement
adds to the necessary overall width of the sheet
10 and causes the offset ends 2 of the blanks to fan
apart and to be spaced away from the lower
longitudinal edge 6, thereby causing more scrap
loss and requiring more steel per sub-rail unit.
Thus, in the usual rectangular mill sheet and
15 with such blank arrangement, it is obvious that
whatever is saved at one side of the sheet by
abutting the wide ends of the blank with the
edge 5, will be lost at the opposite side edge 5
and adjacent bottom edge 6 by the kickup ends
20 being disposed to curve away from one corner
of the sheet to result in more and more scrap
being left at this corner as the number of blanks
per sheet is increased. If alternate blanks be
reversed in lengthwise direction to the others,
25 the kickup ends 2 will engage the wider ends 4
and cause greater spacing of the blanks in these
areas and greater waste between the blanks, re-
sulting in greater widths of sheets required.

Applicant has found that greater economy can
30 be achieved by extending some of the blanks
lengthwise in the same direction and juxtapos-
ing the kickup ends 2 of the blanks on the sheet,
so that the kickups nest closely within one an-
other, as shown in the drawing, which causes
35 their wide ends to spread somewhat or "fan"
out and make allowance for their taper and with
the major portion of the lengthwise edge of the
first blank substantially parallel with the length-
wise edge 6 of the sheet to reduce scrap between
40 the blanks. The succeeding blanks are arranged
with their longitudinal edges substantially co-
inciding with the longitudinal edges of adjacent
blanks. This arrangement disposes the trans-
verse ends of the blanks in stepped relationship,
45 somewhat diagonally of the sheet and results in
producing more of these blanks per unit of
weight, but which inevitably results in the pro-
duction of comparatively large scrap pieces S'
50 at both sides of the rectangular sheet. While
this form of nesting reduces scrap losses between
the individual blanks to a minimum, it obviously
will require an excessive width of sheet, if the
same disposition of blanks is continued all the
way across the width of the sheet.

This growth in the width of the sheet for a

predetermined number of blanks has again been reduced by an arrangement provided by applicant, which contemplates an end to end lengthwise reversal of some of the blanks after a predetermined number have been laid out to extend in one direction as shown in the drawing. In other words, after four blanks have been laid out on the sheet in one direction, the next succeeding group of blanks are laid out in the reverse lengthwise direction, so that the blanks will consume only the minimum amount of stock and will cut down on the width of sheet necessary for the production of a predetermined number of blanks. However, such increase in the number of blanks per ton of sheets requires the use of wider sheets which naturally increases the scrap loss S' in a rectangular sheet as the number of blanks per sheet is increased.

With eight blanks laid out on the old form of rectangular sheet as illustrated in Fig. 2 of the drawing, and with applicant's form of diagonal nesting employed with four blanks reversed end for end with respect to the first group of four blanks, each pair of blanks would weigh 29.37 pounds of steel figured from the gross weight of the sheet, due to the loss of the scrap portions S and S' at the side edges 5 of the rectangular sheet. Such an arrangement would require the width of the rectangular sheet to be 60 $\frac{3}{4}$ ", which exceeds one of the premium cost sheets of 60 inches. Consequently, with such rectangular sheets it is more economical to only blank out six blanks from a single sheet and arrange them in a group of four, with a succeeding group of two blanks reversed end for end with respect to the first group of four, so that the minimum width required for the sheet to produce 6 blanks is 46 $\frac{1}{4}$ inches, making each pair of blanks weigh 29.8 pounds of the gross weight of the entire sheet. Such a sheet is usually $\frac{3}{2}$ of an inch stock, rectangular in shape, measuring 46 $\frac{1}{4}$ inches wide and 75 $\frac{1}{4}$ inches long. This rectangular sheet will produce only six blanks with the best possible nesting. Even with this form of nesting the blanks in groups on the old form of rectangular mill sheets, there is considerable scrap loss at the two side edges 5 of the sheet represented by the areas marked S' in Fig. 2.

In order to avoid this scrap loss incidental in blanking all rectangular sheets, applicant proposed to the steel mills, the use of a rhomboidal sheet of steel 3 shown in Fig. 1, which was contrary to steel mill practice and resulted in the invention of the new continuous diagonal shearing equipment disclosed in the Maddock and Fenton application, Serial No. 242,554 for Blanking apparatus filed November 26, 1938. As no equipment existed in the steel mills for cutting such rhomboidal shaped sheets on any practical or commercial basis, that is to say, on any practical cost basis, the invention required the operation of entirely new automatic equipment for shearing these specially shaped sheets on a continuous strip mill to render it a commercially feasible proposition.

With such rhomboidal shaped sheets economically produced at no more cost than the production of the old rectangular sheets, applicant proposed to nest the blanks B on such sheets so that a line drawn through the ends of such blanks, would be very closely parallel to the inclined opposite side edges of the rhomboidal sheet to entirely eliminate the large scrap areas S' shown in Fig. 2. Thus, with the new form of sheet and arrangement of blanking shown in

Fig. 1, it is possible to obtain eight of the same size sub-rail blanks from a slightly larger sheet measuring 58 $\frac{1}{2}$ inches by 73 $\frac{1}{8}$ inches and with no scrap loss or waste S' at the sides of the sheet.

- 5 For the amount of steel in this rhomboidal sheet 3 in Fig. 1, each pair of the eight blanks requires only 28.37 pounds of the gross weight of the sheet, which represents a saving of 1.31 pounds per pair of blanks. In dollars and cents 10 this results in a saving of .0327 cent per pair of blanks, which, with the slight saving in the necessary pickling cost of the material brings the total saving to .0335 cent per pair of blanks over the six blank sheet measuring 46 $\frac{1}{4}$ by 75 $\frac{1}{4}$. 15 As another example of the savings effected in blanking full length automobile side rails having a forward drop and a rear kickup, it was necessary before this invention to use a rectangular sheet measuring 50 $\frac{1}{2}$ inches by 169 $\frac{1}{8}$ inches 20 equal to 45 $\frac{1}{2}$ pounds per rail. By using the rhomboidal sheet 3 and the method of nesting disclosed herein the dimensions of the sheet can be reduced to 50 $\frac{1}{2}$ inches by 166 $\frac{3}{4}$ inches to obtain the same number of side rail blanks, which 25 from the amount of steel in the sheet, makes each rail require 44.75 pounds of steel for its production, thereby resulting in a saving of .0384 cent per pair of rail blanks including the incidental saving of .0009 cent in pickling costs. In 30 the case of some automobile frames requiring the use of several rhomboidal sheets, it has been found that it is possible to save as much as 10 cents per frame over the cost when rectangular sheets are used.

- 35 These savings are possible in a large degree because the stock is cut in the new shape by the steel mill, since in the usual stock furnished, the loss becomes prevalent in the hands of the fabricator and only when the mill stock is cut up 40 into multiple products and scrap is left over. In other words, the usual rectangular sheet furnished by the mills cannot be blanked and cut by the customer to advantage without material scrap losses. Scrap represents tonnage and since 45 steel is sold by the ton, the customer in every purchase of sheet steel, naturally pays for some that he cannot use to advantage and must dispense with as scrap pieces and trimmings at a loss over the price paid for the steel from which 50 the products are blanked.

- Due to steel mill practice, setup, unusually heavy immovable equipment, and the fact that continuous high speed production of steel strip and sheet is requisite for lower steel prices, these 55 mills have only been able to cut and supply the usual rectangular sheets. This practice has been continued for many years and the practice of blanking from these rectangular sheets has naturally followed and has been used by the 60 fabricators for twenty or more years with no cure used or proposed. With this practice continuing for so many years, without change, it never occurred to anyone prior to applicant how this waste could be avoided.

- 65 The new rhomboidal shape of the sheet 3 is shown in Fig. 1 with opposite pairs of edges parallel and with two of the opposite edges 7 arranged at an angle other than at right angles to the other two opposed parallel edges. In the 70 specific illustration the angle the edges form at a pair of diagonal corners is approximately 82 $\frac{1}{2}$ degrees and at the other pair of diagonal corners is approximately 97 $\frac{1}{2}$ degrees. It will of course be understood that the angles of the rhombus can be varied to suit the particular job in hand.

Fig. 2 illustrates the usual rectangular sheet universally furnished by the mills. The most economical nesting relation of the form of sub-rail blanks illustrated, which is possible in such sheets, is obtained in a sheet measuring 46 $\frac{1}{4}$ inches by 72 $\frac{5}{8}$ inches, from which is obtained as stated before, only six sub-rails and a considerable waste of scrap material at the two sides of the sheet. By making the sheets of rhomboidal outline as shown in Fig. 1, and of very little larger size, namely 58 $\frac{3}{8}$ inches by 73 $\frac{1}{8}$ inches, and nesting the blanks as proposed by applicant and as shown in both figures, eight of the same sized blanks can be obtained at a saving of .0327 cent per pair of blanks. The rhomboidal sheets are obtained by automatically cutting continuously traveling strip steel transversely and obliquely at predetermined intervals. Hand cutting of such sheets would of course be entirely out of the question as it would add more expense and render the price to the fabricator prohibitive.

It is to be understood that nesting arrangements of the blanks other than those disclosed herein may be employed with blanks of other shapes and the scope of the claims is to be limited only by the state of the art.

I claim:

1. The steps in the method of producing an elongated narrow tapered metal blank with lateral co-planar offsets, consisting of providing a flat sheet of metal of rhomboidal shape, and laying out an elongated blank with its longitudinal axis arranged diagonally of said sheet, thereby causing the transverse end edges of the blank to be arranged substantially parallel with the inclined edges of said sheet.

2. The steps in the method of producing elongated flat narrow tapered metal blanks with lateral co-planar offsets, consisting of providing a flat sheet of metal of rhomboidal shape, and laying out a series of tapered elongated blanks with lateral co-planar offsets thereon in such manner that a line drawn substantially parallel with an inclined edge of said sheet passes through the corresponding ends of all of said blanks.

3. The steps in the method of producing elongated flat narrow tapered metal blanks with lateral co-planar offsets consisting of providing a flat sheet of metal of rhomboidal shape, and

laying out a series of tapered elongated blanks with lateral co-planar offsets thereon with the blanks arranged to obtain a greater number of said blanks per ton of sheets than from rectangular sheets of the same size and weight.

4. The steps in the method of producing elongated flat narrow metal blanks with lateral co-planar offsets, consisting of providing a flat sheet of metal of rhomboidal shape, and cutting a series of tapered elongated blanks with lateral co-planar offsets therefrom with the longitudinal edges of the blanks substantially parallel with a pair of opposite edges of the sheet, and the ends of all of the blanks being arranged in stepped relation substantially parallel with the other two opposite edges of the sheet.

5. The steps in the method of producing elongated metal blanks with lateral co-planar offsets, consisting of providing a flat sheet of metal of rhomboidal shape, and cutting a series of tapered elongated blanks with lateral co-planar offsets therefrom with the longitudinal edges of the blanks substantially parallel with a pair of parallel opposite edges of the sheet, and the ends of all of the blanks being arranged in inclined stepped relation substantially parallel with the other opposite inclined and parallel edges of the sheet.

6. The steps in the method of producing elongated tapered metal blanks with lateral co-planar offsets, consisting of providing a sheet of metal of rhomboidal shape, laying out a group of said blanks to extend lengthwise and adjacent the base of the rhombus, with their longitudinal edges substantially parallel with said base and with the ends of said blanks arranged in stepped relation substantially parallel with the inclined side edges of the rhombus, and laying out a second group of said blanks in the same manner adjacent the edge of the sheet opposite said base but in a reverse lengthwise direction and with their ends in stepped relation arranged as a continuation of the first named group and parallel with the same inclined side edges of the rhombus, whereby the ends of all blanks arranged at each inclined side edge of the sheet are disposed on a line substantially parallel with said inclined side edges.

ROBERT H. MADDOCK.
